UNITED STATES PATENT OFFICE.

JAMES A. COLE, OF NORTHLVILLE, NEW YORK.

CARPET-FASTENER.

SPECIFICATION forming part of Letters Patent No. 256,978, dated April 25, 1882.

Application filed December 30, 1881. (No model.)

To all whom it may concern:

Be it known that I, JAMES A. COLE, of Northville, in the county of Fulton and State of New York, have invented certain new and 5 useful Improvements in Carpet and Oil-Cloth Fasteners, &c.; and I do hereby declare the following to be a full, clear, and exact description of the invention, such as will enable others skilled in the art to which it pertains to make 10 and use the same.

My invention relates to an improvement in carpet and oil-cloth fasteners or binding, the object of the same being to provide devices of this character that will be durable and efficient in use, of small initial cost, and adapted, when secured in position, to present a neat and finished appearance.

With these ends in view my invention consists, first, in a carpet or oil-cloth strip composed of two strips of metal, the sides of the upper strip being lapped or bent under the lower strip.

My invention further consists in a binding-strip for carpet or oil-cloth fasteners made of 25 two kinds of metal and provided with diagonal or longitudinal corrugations, as described.

My invention further consists in a binding-strip for carpet or oil-cloth fasteners made of two kinds of metal and provided with diagonal 30 or longitudinal corrugations and bosses or perforations.

My invention further consists in the corner-pieces F and F', made slightly wider than the strips A, and provided at one end with diagonal 35 or longitudinal corrugations and at the opposite end with two or more bosses.

In the accompanying drawings, Figure 1 represents my improvements attached to a carpet or oil-cloth. Fig. 2 represents the corner-pieces in different adjustment; and Fig. 3 is a 40 transverse sectional view of one of the complete binding-strips.

A represents the completed strip, the body portion B of which is composed of any suitable 45 cheap stiff metal—such, for instance, as tin—while the top covering, C, is composed in the present instance of thin rolled brass strips slightly wider than the strips B, so as to allow the sides or edges to be turned under the said 50 strips B and secure it thereto.

The two portions B and C can be secured together by any suitable means, and are pro-

vided with either longitudinal or diagonal corrugations D, which increase the strength of the binding and enable the sections to be accurately fitted to each other and be retained in position. The securing together of the portions B and C can be accomplished in the same operation by which the strips are corrugated by means of suitable rolls or dies. The strips 55 thus formed are provided at suitable distances apart with the bosses E, the latter being provided centrally with a hole, a, for the passage of a tack by which it is secured to the floor. Instead of providing the bosses, suitable holes can 60 be provided to answer all the necessary purposes. The strips A, however, can be left imperforate to be pierced by the tacks when put down, or they can, as before stated, be perforated during the process of corrugating. One of the most 65 important functions fulfilled by the corrugations is the strengthening of the strips, thereby preventing them from becoming distorted in shape when pressure is applied thereon, and it also prevents the sides from curving up and 70 presenting rough and sharp edges, against which articles of clothing are likely to catch. By providing the strips A with the bosses E the under sides of the same are drawn into close 75 contact with the carpet or cloth, thus holding the same firmly in place and preventing the edges or sides opposite the tack from curling or rising up and presenting edges against which moving furniture, &c., would be likely to engage. These corrugations and bosses 80 have been described in previous patents granted to me, and require no further special mention in this case.

The corner-pieces F can be made of two kinds of metal, similar to the strips A, already referred to, or they can be made wholly of the metal composing the top C of the strip A, so 85 as to notch therewith.

Each corner-piece consists of two sections, F', formed partly of either longitudinal or diagonal corrugated strips of metal, both of the said sections F' being provided at one end 90 with two or more bosses, E, formed on the upper faces of the strips, and each boss consisting of one or more concentric circular corrugations.

In attaching a corner-piece to a carpet or oil-cloth the boss of one section is placed upon that of the other section, which forms a bear-

ing or pivot for it, the corrugation or corrugations forming the boss of the lower section being received within the depressions in the under surface of the boss of the upper section, caused by the formation of the raised corrugations on its upper surface. After the two sections are adjusted upon each other, as described, they are secured together by a tack or suitable pin, *c*, which passes through the holes *a*, formed in the center of each boss. The said pin *c* forms a pivot upon which the two sections can be turned to assume any desired adjustment.

The corner-pieces *F'*, as before stated, are provided at one end with two or more bosses *E*, (in the present instance three,) and are made a little wider than the strips *A*, so that the sides of the same can project over the sides of the said strips *A*, thereby avoiding punching holes in the strips *A*, where they have not been formed, for the purpose of securing it to the floor. When the central bosses *E* of the pieces *F* have been employed for securing the corner-pieces, as shown in Fig. 1, the extreme outer ends of the pieces *F* and *F'* project over the oil-cloth and are secured by the pin *c* through the boss *E* to the carpet or floor, thereby making a smoother artistic finish at the corner, that presents no obstructions or raised edges. It may be necessary sometimes to connect the outer end bosses *E* of the pieces *F'* together to enable the corner-pieces to be properly fitted and connected to the side strips, *A*, and in this case the end bosses *E* can be secured together, thereby leaving no extending or projecting end, and when there is plenty of material for connecting the parts, the extreme inner end bosses *E* may be used, thereby leaving extending or projecting ends which are tacked to the carpet or floor, and present a neat and

finished appearance. The bosses on the ends of the corner-pieces *F'* can be formed any suitable distances apart, so as to allow of adjustment in case the side strips should be a little shorter than necessary. As the strips *A* are corrugated on both sides, the reverse or under side of the strips *A* may be turned upside down and secured, thereby giving a binding with a tin center and a colored brass border.

By making the strips *A* of two metals, as before described, I produce a cheap stiff binding that can be manufactured at a small initial cost, and, together with the corner-piece, form, when put together, a neat, tasty, and durable binding that is equally well adapted for carpets and oil-cloths.

I would have it understood that I do not limit myself to the combination of any particular metals to form my improved binding, and I do not limit myself to the exact construction of parts shown and described, but consider myself at liberty to make such changes as come within the spirit and scope of my invention.

Having fully described my invention, what I claim as new, and desire to secure by Letters Patent, is—

The corner-pieces *F* and *F'*, made slightly wider than the strips *A*, and provided at one end with diagonal or longitudinal corrugations and at the opposite end with two or more bosses, substantially as and for the purpose described.

In testimony whereof I have signed this specification in the presence of two subscribing witnesses.

JAMES A. COLE.
